UNITED STATES PATENT OFFICE.

SAMUEL S. FRETZ, OF PHILADELPHIA, PENNSYLVANIA.

DESIGN FOR A HOLLOW UMBRELLA-ROD.

SPECIFICATION forming part of Design No. 35,255, dated November 5, 1901.

Application filed August 10, 1900. Serial No. 26,536. Term of patent 14 years.

To all whom it may concern:

Be it known that I, SAMUEL S. FRETZ, a citizen of the United States, and a resident of the city and county of Philadelphia, in the

State of Pennsylvania, have invented and produced a new and useful Design for a Hollow Umbrella-Rod, of which the following is a specification, reference being had to the accompanying drawings.

Figure 1 is a view of the entire rod in side elevation. Fig. 2 is a longitudinal sectional view of the rod. Fig. 3 is an enlarged view in elevation of the right-hand portion of Fig. 1. Fig. 4 is a longitudinal sectional view of Fig. 3.

The characteristic features of the design consist in a short end portion of a tapering shape, a relatively long body portion of uniform thickness and smaller diameter than the

end portion, an abrupt taper uniting the end portion and body portion, and both said por-

tions having a continuous central passage or hole constituting a hollow rod circular in cross-section, the opening of which is shown at the end.

A is the short tapering end portion, and B the relatively long body portion of uniform diameter and having an opening at the end. At the meeting-point of the short tapering portion and the relatively long body portion is an abrupt taper, as clearly shown by the figures of the drawings.

Having now described my invention, what I claim as new, and desire to secure by Letters Patent, is—

The design for an umbrella-rod as herein shown and described.

SAMUEL S. FRETZ.
